REINHARD HILDEBRAND, OF WEBSTER GROVES, MISSOURI, ASSIGNOR OF ONE-HALF
TO GEORGE D. POGUE, OF PHILADELPHIA, PENNSYLVANIA.

CROSSHEAD DESIGN FOR RECIPROCATING ENGINES.

Application filed April 8, 1919. Serial No. 288,618.

To all whom it may concern:

Be it known that I, REINHARD HILDEBRAND, a resident of Webster Groves, in the county of St. Louis and State of Missouri, have invented a new and useful Improvement 5 in Crosshead Designs for Reciprocating Engines, of which the following is a specification.

This invention relates to engines and 10 machines of the type that comprise a piston connected to a reciprocating cross head that is operated from a crank shaft.

One object of my present invention is to provide an engine or machine of the general 15 type referred to which is so constructed that the piston can be arranged in a position where it can be inspected or repaired without disconnecting it from the cross head or dismantling numerous parts of the machine 20 or engine.

Another object is to provide a cross head structure for machines and engines of the character referred to that is inexpensive to manufacture, easy to adjust and of such design 25 that equal pressure on the cross head guides is assured at all times, irrespective of the direction of rotation of the crank shaft.

Figure 1 of the drawings is a front elevational view of a portion of an internal combustion engine equipped with a cross head constructed in accordance with my invention.

Figure 2 is a top plan view of Figure 1, 30 taken on the section line 1-1 of Figure 1, the slide shoes and the guides for said shoes being shown in section and the connecting rod omitted.

Figure 3 is a view, taken at right angles 40 to Figures 1 and 2, illustrating a portion of the cylinder and showing how the piston can be arranged in position to be inspected or repaired by rocking the cross head relatively to the slide shoes that guide the cross head vertically, said view being taken on approximately the section line 2-2 of Figures 1 and 2; and Figure 4 is a view similar to Figure 3, showing the upper end portion of the piston projecting into the 45 cylinder.

Referring to the drawings which illustrate the preferred form of my invention, A designates the cross head proper which consists of a substantially square body having two

wrist pins or cross head pins B, each of 55 which is equipped with a cylindrical extension C. The connecting rod D, which is of the forked type, is provided with two wrist pin bearings E that surround the cross head pins B. A piston rod F which joins the 60 piston V to the cross head, passes through the cross head, as shown in Figures 3 and 4, and is secured to the cross head by means of a nut H that draws a collar G on the piston rod snugly against the cross head. The 65 cross head is guided vertically by means of slide shoes K that reciprocate vertically in guides J, said slide shoes being relatively long, as shown in Figure 1, and being mounted on the cylindrical extensions C on 70 the cross head, thereby enabling said shoes to turn and adjust themselves relatively to the cross head in order to align properly with the guides J and also permitting the cross head to be turned or oscillated so as 75 to move the piston V out of alignment with the cylinder, as shown in Figure 3 when it is desired to inspect or repair the piston. The slide shoes K are provided with shims M and keeper strips L, said strips being connected to the shoes by bolts N. After the keeper strips L have been removed the 80 shoes K can be disconnected from the cross head by pulling them off the cylindrical extensions C on which said shoes are mounted. 85 By connecting the cross head to the slide shoes in this manner I obtain equal pressure 80 per square inch shoe area, whether the crank shaft is running forwardly or rearwardly, and I reduce the cost of manufacture and 90 installation of the cross head structure.

The main advantage of such a structure, however, is that when used in connection with a cylinder provided at its lower end with a removable portion or skirt, the piston can be arranged in such a position that it can be inspected or repaired without disconnecting the piston from the cross head or disassembling the main parts of the machine or engine. In Figures 3 and 4, O 95 designates the cylinder in which the piston V slides, P the water jacket that surrounds the cylinder and Q a removable extension on the lower end of the cylinder O that is normally connected to same, as shown in 100 Figure 4, by bolts passing through holes d in the extension Q and threaded into openings e in the lower end of the cylinder lin-

ing, the removable extension Q of the cylinder being provided with a drip pan R fastened to same by means of bolts S.

When it is desired to inspect or repair the piston V the extension Q at the lower end of the cylinder is disconnected therefrom and slipped downwardly over the piston rod F, as shown in Figure 3, said extension Q being retained in position on the piston rod 10 by means of a split sleeve W and split nut Z that are applied to said piston rod and retained in position by means of bolts X and Y that connect the two portions of said sleeve and said nut together. The sleeve W fits snugly around the piston rod, with its lower end bearing against the collar G on said piston rod, and the nut Z is adjustably mounted on an externally screw-threaded portion of said sleeve, so as to permit the extension Q to be raised or lowered, or, in other words, moved longitudinally of the piston rod by rotating the nut Z, said nut being provided with a number of holes f in which a bar can be inserted to turn said nut. After the cylinder extension Q has been disconnected from the cylinder, dropped downwardly over the piston rod and sustained in position on said piston rod by means of the sleeve W and nut Z, as previously described, the cross head can then be turned so as to swing the piston laterally out of alignment with the cylinder, it, of course, being understood that the crank of the crank shaft (not shown) is then in its lower dead center position and the cross head is in its lowermost position. Any preferred means can be used for swinging the piston laterally out of or into alignment with the cylinder O, the means herein illustrated for this purpose consisting of a rope 30 or cable b connected to the cylinder exten- 35

sion Q and passing over a pulley a attached to some stationary part of the machine, such, for example, as to an eye bolt on the water jacket of the cylinder. After the piston has 45 been inspected or repaired it is moved back into vertical alignment with the cylinder, the nut Z is then turned in a direction to move the extension Q upwardly so as to force a tongue T on the upper end of said extension into an annular groove U in the lower end of the cylinder, said extension is then secured to the cylinder and the nut Z, sleeve W and cable and pulley are then removed, as shown in Figure 4. While I have 50 herein illustrated my invention embodied in a machine provided with a vertically movable cross head, it will, of course, be understood that my invention is applicable to 55 a machine provided with a cross head that 60 slides horizontally.

Having thus described my invention, what I claim as new and desire to secure by Letters Patent, is:

In a machine of the character described, 65 a cylinder, an extension at the lower end of said cylinder detachably connected to same, a piston that operates in said cylinder, a reciprocating cross head, a piston rod that rigidly connects said cross head to said piston, parallel guides arranged adjacent the 70 opposite ends of said cross head, slide shoes in said guides, said crosshead being pivotally mounted on said slide shoes, and a removable means mounted on said piston rod for 75 sustaining said cylinder extension after it has been disconnected from the cylinder.

REINHARD HILDEBRAND.
